UNITED STATES PATENT OFFICE.

HARLEY M. DUNLAP, OF BATTLE CREEK, MICHIGAN.

BIFURCATED GARMENT.

No. 924,751.

Specification of Letters Patent.

Patented June 15, 1909.

Application filed May 20, 1905. Serial No. 261,396.

To all whom it may concern:

Be it known that I, HARLEY M. DUNLAP, a citizen of the United States, and a resident of Battle Creek, in the county of Calhoun, State of Michigan, have invented certain new and useful improvements in Bifurcated Garments, of which the following is a specification.

This invention relates to improvements in bifurcated garments.

It is particularly adapted to those garments known as "union suits", although it is of advantage for use in other relations.

The objects of this invention are: First, to provide an improved union suit (bifurcated garment) of simple and efficient construction. Second, to provide an improved union suit (bifurcated garment) having a closed crotch and a posterior opening and closure therefor of convenient access, adapted for the use of men, women and children. Third, to provide an improved union suit (bifurcated garment) by which the principal objectionable features of both union suits and two-piece garment suits are overcome. Fourth, to provide an improved bifurcated garment having a suitable opening, in which the crotch and such opening are normally perfectly closed. Fifth, to provide in a nether garment an improved flap or closure having sufficient fullness to conform to the shape of the body of the wearer in whatever position it may be.

Further objects, and objects relating to structural details, will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing, forming a part of this specification, in which:

Figure 1 is a detail elevation of the posterior portion of a garment embodying my improvements. Fig. 2 is a detail elevation of the posterior portion of a garment embodying my improvements before the flap or closure 9 is applied, the parts being illustrated in conventional form, the flap being indicated by dotted lines. Fig. 3 is an enlarged section taken on a line corresponding to line 3-3 of Fig. 2, showing the relation of the flies 4 and 5. Fig. 4 and Fig. 4^a are sectional views taken on lines corresponding to

lines 4-4 and 4^a-4^a of Fig. 2, further showing the relation of the flies 4 and 5 to the garment proper. Fig. 5 is a plan view of the flies 4 and 5. Fig. 6 is a plan view of the flap sections 10. Fig. 7 is a detail view of a modified construction.

In the drawings, similar reference characters refer to similar parts throughout the several views, and the sectional views are taken looking in the direction of the little arrows at the ends of the section lines.

Referring to the drawing, the garment 1 is provided with a quadrilateral opening 2 in its posterior portion, located just above the crotch, as is indicated clearly in Fig. 2. A slit 3 extends upwardly from the apex of this opening, the slit preferably terminating somewhat below the waist line. A pair of flies, as 4 and 5, which are preferably triangular in shape, are arranged one on the inside and the other on the outside of the garment, as clearly appears in Fig. 3. The outside fly 4 is stitched at its inner edge to one edge of the slit 3, and the inside fly 5 is stitched at its inner edge to the other edge of the slit so that when the edges of the slit are separated, the flies overlap, the stitching for the outer fly to the edge of the slit being indicated by the reference numeral 6, while that of the inner fly is indicated by the reference numeral 7. The flies 4 and 5 are also stitched along their upper edges to the body of the garment, the stitching being indicated by reference numerals 8-8, see Figs. 4 and 4^a.

The flap 9 is preferably made up of sections 10-10, which are stitched together along their inner edges, the pieces being cut to a suitable pattern, as indicated, so as to secure the desired fullness which conforms the flap to the hips. In securing the flap, its edges 11 are stitched along the lower edges 12 of the opening 2, and its edges 13 are stitched along the garment on the dotted lines 14, see Fig. 2. This gives a fullness to the seat of the garment. The flap 9 is of such size that it covers the lower portion of the slit 3 when the flap is closed, and, at the same time, the upper edge of the flap is arranged so that it is below the waist line of the wearer. Suitable buttons, as 15, or other fastening devices are provided for securing the flap or closure. The flies 4 and 5 and the flap 9 are preferably made of the same fabric as that of the garment, although any suitable material may be used.

In the modified construction shown in Fig. 5, the flap 16 is cut out from the body of the garment and the flies 17, which are indicated by dotted lines, are attached to the 5 garment at their upper edges and their outer edges are attached along the edges to the openings, as is indicated by the dotted lines, the flaps thus overlapping. This construction, however, lacks many advantages of 10 that shown in the preferred construction.

My improved garment is simple in structure and at the same time is very desirable and convenient. The opening in its normal condition is perfectly closed. My improved 15 garment is adapted for the use of men, women and children.

By attaching the flap 9 as I have described, the desired fullness in the seat is secured to accommodate the body in any position. 20 By forming the flap of sections, as illustrated, the desired fullness to conform to the hips is secured.

I have illustrated and described my improved bifurcated garment in detail in the 25 form preferred by me on account in its structural simplicity and convenience in use. I am, however, aware that it is capable of considerable variation in structural details without departing from my invention.

Having thus described my invention, what 30 I claim as new and desire to secure by Letters Patent, is:

1. A nether garment having a quadrilateral piece removed therefrom to form an 35 opening and having a slit extending upwardly from said opening; a pair of triangular-shaped flies, each of which is secured along its inner edge to one of the edges of said slit, one of said flies being arranged on the inside 40 and the other on the outside and secured along their upper edges so that when the edges of said slit are separated the flies overlap, and a heptagonal flap or closure having its lower edges secured to the lower edges of 45 said opening and adapted, when closed, to cover the lower portion of said slit.

2. A nether garment having a piece removed therefrom to form an opening and

having a slit extending upwardly from said 50 opening; a pair of flies, each of which is secured along its inner edge to one of the edges of said slit, one of said flies being arranged on the inside and the other on the outside and secured along their upper edges so 55 that when the edges of said slit are separated the flies overlap, and a flap or closure having its lower edges secured to the lower edges of said opening and adapted, when closed, to cover the lower portion of said slit.

3. A nether garment having an opening 60 therein; a slit extending upwardly from said opening; a pair of flies, each of which is secured along its inner edge to one of the edges of said slit, one of said flies being arranged on the inside and the other on the outside 65 and secured along their upper edges so that when the edges of said slit are separated the flies overlap, and a flap or closure having its lower edges secured to the lower edges of said opening and adapted, when closed, to cover 70 the lower portion of said slit.

4. A nether garment having a posterior opening; a pair of flies, each of which is secured along its inner edge to one of the edges of said opening, one of said flies being arranged on the inside and the other on the outside 75 and secured along their upper edges so that when the edges of said opening are separated the flies overlap, and a flap or closure arranged to open downwardly. 80

5. A nether garment having a posterior opening; a pair of flies, each of which is secured along its inner edge to one of the edges of said opening, one of said flies being arranged on the inside and the other on the outside 85 and secured along their upper edges so that when the edges of said opening are separated the flies overlap, and a flap or closure arranged to open downwardly, the lower portion of said flap being formed with a fullness. 90

In witness whereof I have hereunto set my hand and seal in presence of two witnesses.

HARLEY M. DUNLAP. [L. S.]
